GRID PASTING MACHINE

Arthur D. Lund, Minneapolis, Minn.

Application May 21, 1934, Serial No. 726,744

52 Claims. (Cl. 226—39)

This invention relates to machines for pasting storage battery grids, and the primary object is to provide an efficient, practical, and relatively high speed machine for applying the pasty active material to the grid, for completely filling the grid spaces or interstices with the material, and then properly finishing the grid surface so that it will be complete as a unit for battery use. The machine comprises in cooperative relationship a series of correlated mechanisms including a receptacle for holding a vertical stack of unpasted grids, to be replenished as the stack is reduced in size; a stripper mechanism for removing one plate at a time from the bottom of the stack; a platen for receiving the successively stripped plates and placing them vertically in a lowering device; means for actuating the lowering device to feed the plates to the pasting rolls; means for preventing gaps between the grids as they travel through the paster device; and novel paste applying, rerolling, and conveyor structures, together with novel adjustments and control mechanisms, all of which will be more fully described in the following specification, reference being had to the accompanying drawings, wherein:

Fig. 1 is a side elevation of the machine, and for purpose of convenience in reference the right end of the machine, as seen in this figure, will hereinafter be considered as the front or forward end.

Fig. 1A is an enlarged detail view of a portion of the platen actuating mechanism.

Fig. 2 is a side elevation of the machine as seen from the opposite side from that illustrated in Fig. 1.

Fig. 2A is a detail elevation of a portion of the front end of the machine as seen on the line 2A—2A in Fig. 2.

Fig. 3 is a top or plan view of the machine as looking down upon the same in Fig. 2, and with the right or rear end thereof broken away and with other parts omitted or in section for purpose of illustration.

Fig. 4 is a sectional detail elevation through the grid plate stripper carriage as seen on the line 4—4 in Fig. 3.

Fig. 5 is a sectional elevation taken longitudinally through the machine, and primarily through the center thereof, although in certain instances the section runs through a plane offset with respect to the transverse center.

Fig. 6 is an enlarged, detail sectional elevation through the paste feeding and applying rolls as shown on a smaller scale in Fig. 5.

Fig. 7 is an enlarged, sectional elevation corresponding to the left end portion of Fig. 5, but showing the platen in its raised or vertical position, and with other actuating parts in the positions which they assume when the platen is thus raised.

Fig. 8 is an enlarged, detail view of one of a pair of devices employed to frictionally engage and thus retard the downward movement of the grid plates as they leave the paste applying mechanism, and are delivered to the conveyor, which transfers them to what is known as the reroll apparatus or mechanism.

Fig. 9 is an enlarged, detail side elevation of a portion of the platen actuating and grid feeding mechanism generally referred to as a lowering device.

Fig. 9a is another portion of the platen actuating and grid feeding mechanism, partly in section as on the line 9a—9a in Fig. 10, this portion being operatively connected with the portion shown in Fig. 9, through the shaft 127.

Fig. 10 is a sectional, detail view as seen on the irregular line 10—10 in Fig. 9.

Fig. 11 is an enlarged, detail elevation of certain parts of the reroll and plate conveyor mechanism, as shown in Fig. 2, with the upper end portion in section as on the line 11—11 in Fig. 12, and with the reroll belts and belt supporting and engaging devices in section on a vertical plane somewhat inwardly from the side of the machine.

Fig. 12 is a sectional, detail plan view as on the line 12—12 in Fig. 11.

Fig. 13 is a plan view of the grid plate aligning and lowering device which receives the plates from the reroll mechanism and delivers them to a conveyor therebelow, this view having various parts broken away to facilitate illustrating certain features.

Fig. 14 is a detail elevation on the line 14—14 in Fig. 13.

Fig. 15 is an enlarged, sectional plan view as seen substantially on the irregular line 15—15 in Fig. 5.

Referring to the drawings more particularly and by reference characters, 20 designates a main frame or hollow base, and includes two heavy cast side walls 21 connected by suitable cross members such as 22, and also by the housings and other superstructures presently to be described. At the rear end of the machine the side frame members 21 are provided with longitudinal casting extensions 23 secured thereto by bolts 24. Secured to the base structure 20 is a

20

25

40

45

50

55

driving motor 25 which provides power for the entire machine. This motor has a shaft 26 which drives a shaft 27 through the medium of sprocket gears 28 and 29, and a sprocket chain 30. The shaft 27 extends transversely through the base in which it is journaled, and at the end opposite from the sprocket gear 29 is provided with a sprocket pinion 31 which operates through a sprocket chain 32 to drive a sprocket gear 33 on a transverse shaft 34 as shown in Fig. 1. The shaft 27 also drives a laterally disposed, inclined shaft 35 through the medium of bevel gear 36 and a bevel pinion 38, the shaft 35 being journaled in a series of bearings 39, 40, and 41. 15 Adjacent the bearing 40 the inclined shaft 35 has a worm screw 42 for driving a worm gear 43 on a shaft 44. At its upper or front end the shaft 35 has a bevel pinion 45 which meshes with and drives a bevel gear 46 on a stub shaft 20 47, which shaft 47 has a spur gear 48 for driving a second gear 49 which is mounted for rotation on a shaft 50, the members 49 and 50 being shown in detail in Fig. 10.

Referring again to Fig. 2, it will be seen that the driven end of the shaft 27 operates through gears 51 and 52 to drive a shaft 53 which also extends through the base structure, and is provided at its opposite end, as shown in Fig. 1, with bevel pinions 54 to thus transmit power to a rearwardly extending, laterally arranged shaft 55. This shaft 55 has a worm screw 56 for driving a worm gear 57 on a stub shaft 58; and the rear end of the shaft 55 operates through bevel pinions 59 to transmit power to a shaft 60, and this shaft 60 in turn drives one of the reroll shafts 61 through sprocket gears 62 and 63, and sprocket chain 64, as shown in Fig. 1. The other reroll shaft 65 is driven from the shaft 53 by sprocket gear 66, sprocket chain 67, and sprocket gear 68. Thus it will be seen that when the motor 25 is running it will supply power to all of the transversely disposed shafts 27, 34, 44, 47, 53, 58, 60, 61, and 65, and to the gear member 49 mounted for rotation on and sometimes with the shaft 50.

Upon the front end of the base structure 20 is mounted a carriage unit designated generally by the numeral 69, which unit carries a considerable portion of the operating mechanism and is mounted for a limited reciprocating motion on the base 20. Extending laterally from the unit 69 are two flanges 70 (see Fig. 2A) which are slidable in channels formed by recesses in the upper ends of the base walls 21, and cover plates 71 secured to the base walls by bolts 72. The channels for the flanges 70 are preferably more restricted at their rear ends, and adjacent these forward points the cover plates 71 are secured by bolts 73 which, when tightly screwed down will exert a clamping and retaining action on the flanges 70, and thus rigidly secure the carriage unit 69 in adjusted positions.

At its forward end the carriage 69 is provided with a pair of laterally extending lugs 74 in which are adjustably secured set screws 75, the purpose of which is to contact with the front end edges of the walls 21 to thereby adjustably limit the forward motion or movement of the carriage 69 with respect to the main frame of the machine. These stop bolts 75 are of course preferably provided with lock nuts 76 so as to secure them in the variously adjusted positions.

The unit 69 comprises an irregularly shaped

member including a rear wall 77, a bottom plate 78, and a short front wall 79 to which is hingedly secured as at 80 a door 81 having a knob 82, and at its top the chamber 83 formed by these members is closed in part by a lid 84 hinged as at 85. 5 Side walls substantially complete the enclosure of this chamber, but they continue rearwardly and downwardly beyond the members 77 and 78, as best shown in Fig. 7, to form supports for other parts of the machine presently to be described. 10 These rearwardly extending side walls, it may here be noted, are connected by a shelf member 86, and also by an inclined chute forming plate 87 which has for its purpose to direct and discharge surplus paste material which has not 15 been worked into the grid plates to be treated.

The carriage unit is slidably adjusted by a hand lever 88 which is mounted on a shaft 89 journaled in the base structure 20, and this shaft, at a point intermediate its ends, is provided with a crank 90 20 (see Fig. 7) which is in turn connected by a link 91 to a depending lug 92 of the chamber portion of the carriage.

It will now be seen that by loosening the clamping bolts 73 the entire carriage may be shifted 25 back and forth by manipulating the hand lever 88, and to the extent permitted by the stop bolts 75 in one direction, and to an amply sufficient degree in the other direction.

Upon the top of the carriage and between the 30 lid 84 and the platen presently to be described, I mount a pair of laterally arranged guide plates 93 forming a chamber for a stack of grids 94 which are to receive treatment. These grids are stacked in such a manner that they may be 35 stripped off, one at a time, from the bottom of the stack and be moved forwardly upon the platen one at a time. This stripping action is effected by a stripper plate 95 having substantially the same thickness as one of the grid plates so that as 40 it moves rearwardly against the forward edge of the lowermost grid it will push the same rearwardly from under the stack and deliver it to the platen. The stripper plate 95, as shown particularly in Fig. 4, is guided at its side edges in 45 grooves 96 formed by recessed bars 97 secured by bolts 98 upon the upper side portions of the chamber housing. The stripper plate is secured along a central line to a traveler block 99 which operates in a slot formed in the top portion 100 of the 50 chamber housing, and immediately below this top portion I provide the block 99 with a pair of oppositely directed flanges 101 for sliding engagement in a race formed by a pair of guide bars 102.

At its forward or left end, as shown in Fig. 7, I 55 provide the stripper plate 95 with a pair of reinforcing cross bars 103 which are also secured to the block 99. The stripper unit is reciprocated by a link 104 which is pivotally connected as at 105 to a lug of the block 99, and is also pivotally 60 secured at its other end to a left arm 106 which is fulcrumed as at 107 to a lug 108 in the bottom of the chamber 83. Intermediate its ends the lever 106 is connected by a connecting rod 109 to a trunnion pin 110 projecting from a cam 111 which 65 in turn is carried on the inner end extremity of the shaft 50 previously referred to. Thus it will be seen that when the shaft 50 is rotated it will operate through the members 111, 110, 109, 106, and 104 to actuate the stripping mechanism.

Attention is now directed to Fig. 10 and the right end portion of Fig. 9, wherein is disclosed the mechanism for rotatably connecting and disconnecting the gear 49 with respect to the shaft 50. Secured by bolts 112 to the outer face of the 75

gear 49 is a cam ring 113, the outer peripheral edge of which is divided into four equal cam portions, and one end of each of these cam portions presents an inclined shoulder 114 for engagement by a pawl 115 which is pivoted as at 116 in a projecting portion of a cup-like member 117, which member substantially encloses the cam ring 113, but has a hub portion which is keyed or otherwise rigidly secured upon the shaft 50. The pawl 115 is free to move through a peripheral opening 118 in the cup member 117; and when it is in its inward position it will engage one of the shoulders 114 so that when the cam 113 is rotated in the direction of the arrow shown in Fig. 9 it will engage the pawl 115 to thereby rotate the cup member 117 and shaft 50 in unison with itself.

To disengage the pawl 115 from the cam ring 113 so that the shaft 50 will not be rotated with the gear 114, I provide a lever 119 which is fulcrumed as at 120 to a bearing lug 121 of the cup member 117, and this lever has one finger or short end portion 122 in contact with a tooth 123 of the pawl 115, as shown in Fig. 10. The other or relatively longer end of the lever 119 is bifurcated 25 so that the two arms thereof will be disposed at opposite sides of the outer hub portion of the member 117, and will be so arranged that when pressed inwardly the finger 122 will engage the tooth 123 to thereby disengage the pawl 115 from the cam ring. The lever 119 is actuated to produce this disengagement by a collar 124 which is slidably keyed on a reduced end portion of the shaft 50 and is adapted to be pushed inwardly against the lever 119 by a bell crank lever 125 30 which is fulcrumed as at 126, and is in turn actuated by a rod 127 which extends rearwardly and upwardly so as to be operatively associated at its upper end with the platen and lowering mechanisms.

When the rod 127 is not being pulled or actuated rearwardly under the influence of the platen and lowering mechanism, it reposes in a normally forward position, at which time the bell crank lever 125 exerts no inward pressure against the lever 119, and at such time the pawl 115 is maintained in contact with one of the shoulders 114 of the cam rim 113 under the action of a spring 128 contained within a small chamber or cylinder 129. This spring is attached to the pawl 115 at one end while its other end is attached to a threaded bolt or bar 130 which is adjustably secured as by a nut 131. The tension of this spring 128 is such that it will yieldably maintain operative contact as between the pawl and the shoulder 114 which it engages. However, it should be noted that the contact surfaces as between the end of the pawl and the shoulders are slightly angled with respect to a radial line passing through the point of contact so that should the resistance become excessive the pawl will ride over the cam shoulder to thus prevent any breakage of parts under abnormal operating conditions.

The purpose of the mechanism illustrated in Figs. 9 and 10 is to momentarily stop the grid feeding and platen operating mechanism in connection with a certain mechanism for eliminating gaps as between the successive plates to be treated and to insure such plates being in edge to edge contact as they pass into the pasting devices. Thus it will be seen with particular reference to Fig. 7 that when the shaft 50 stops, the stripping mechanism operated by the connecting link 109 will also be idled. Similarly the cam 111 which operates the lowering device and a cam 75 132 also mounted on the shaft 50 will cease to

operate the platen tilting apparatus. The cam 111, which is somewhat kidney shaped in form, travels or rotates under a roller 133 mounted in one end of a lever 134 fulcrumed in the carriage 69 as at 135, the opposite end of this lever being 5 arranged to engage the roller 136 on an arm 137 of a shaft 138 which extends through the wall of the housing, and at its outer end has a lift arm 139 upon one end of which rests a rod 140 slidably mounted in suitable bearings and having a 10 spring 141 for maintaining contact between the lower end of the rod and the lift arm 139. The upper end of the rod 140 engages under a roller 142 mounted in the one end of an arm 143 secured on a shaft 144, and which shaft also has 15 a relatively longer arm 145 which is pivotally connected at its rear end as at 146 to the lowering device frame designated generally by the number 147.

The cam 132 within the chamber 83 engages 20 a roller 148 on an arm 149 of a shaft 150, which shaft is journaled in one side wall of the chamber, and at its outer end is provided with a crank arm 151 (see Figs. 1 and 1A), the upper end of which crank arm is pivoted as at 152 to a length adjustable connecting rod 153, the other or rear end of which is pivoted as at 154 to the platen block or frame. This block or frame includes the platen plate proper, designated as 155, from which extend two rigid arm portions 156 which 30 terminate outwardly from the carriage walls in a pair of integral, substantially triangular end pieces 157. These end pieces are preferably partly enclosed by shell-like members 158, which members also constitute bracket extensions that are secured to the carriage 69 by bolts 159. The members 157 are respectively fulcrumed by pins 160 which are trunnioned in the bracket members 158. It will thus be seen that when the bar 153 is reciprocated under the action of the cam 132 40 when the latter is rotating, the platen plate 155 will be moved from the vertical position, as shown in Figs. 7 and 9, to the substantially horizontal position as indicated in Figs. 1, 1A, 3, and 5, in which horizontal position the platen is arranged 45 to receive the successive grid plates as they are stripped from in under the stack of plates 94, and from thence carried to the vertical position as shown in Fig. 7, at which time such plates are 50 in a position to be lowered into the pasting apparatus.

At the opposite sides of the platen the carriage frame is provided with a pair of guiding plates 161, which plates are each provided in their inner sides with two arcuate channels 162 and 163, the purpose of which is to receive lug extensions 164 of the grid plates, which extensions or ears are invariably present in battery grid plates and are usually arranged in the manner indicated in Fig. 3, under which circumstances they would be engaged by the channels 162, although in some instances and for some types of plates it is desirable to have the lugs spaced inwardly from the corner of the plate, and under such circumstances they would 60 be guided in the channels 163 of the guide plates 161. These channels, it may be noted with particular reference to Fig. 7, are somewhat narrower at their top ends than at their lower ends, the purpose being that they might more readily 65 receive the grid plate ears and then more accurately guide them into the receiving position by the lowering device. To facilitate the pressing of the grid plate ears into receiving contact with the lowering device it is also preferable to pro- 70 75 75

vide the platen proper with ears such as indicated at 165 in Fig. 3, which ears will engage in the channels 162 and 163 immediately behind the grid plate extensions. In order that grids 5 having their ears disposed further from the corner of the plate may engage in the curved channels 163, it is necessary to provide clearance at the lower ends of the plates 161, and this clearance for the ears is indicated as at 66 in Fig. 7 10 and Fig. 9.

In order to insure proper placement of the grids on the platen after each grid leaves the stack and before the platen starts to move to its vertical position, I provide a friction shoe 15 167 for lightly engaging and bearing down upon the grid as it moves outwardly from in under the stack and is placed upon the platen. This shoe is preferably made of flexible metal, and when in operative position is downwardly inclined as indicated by the dotted lines in Fig. 2. However, before the platen can be moved to its grid discharging position it is necessary for the shoe 167 to be removed from the path of travel, and for that reason I mount it upon a 20 shaft 168 which is journaled in lug extensions 169 of the guide plates 161, and at one end this shaft 168 has an arm 170 connected by a link 171 to an arm 172 which connects with the platen frame member 157 on the side of the machine 25 shown in Fig. 2. Consequently when the platen is moved up and down it will operate through the members 170, 171, and 172, to clear the friction shoe during each movement and also to place the shoe back in operative position during the intervals when the stripped grid plates 30 are being placed on the platen.

It may here be noted that the shaft 144 of the lowering device operating arm 145 is journaled in a bracket 173 which is rigid with respect to 40 the main frame of the machine and does not move with the carriage unit 69. The lift rod 140, on the other hand, does reciprocate with the carriage unit, and therefore is horizontally movable with respect to the roller 142 of the 45 arm 143. Consequently when the carriage is moved forwardly or to the left, as shown in Fig. 7, the roller 142 will disengage from the top of the lift rod 140 and will naturally drop down a short distance under the gravitational 50 action of the lowerator 147. Consequently, and to restore the roller 142 to its normal operative position when the carriage is again moved rearwardly or to the right, I provide the upper end of the rod with a wedge shaped lift arm 174 upon 55 which the roller 142 may ride, both when moving down from and back up to the top of the lift rod. The lowering unit comprises a block 175 that is vertically movable upon a central post 176 rigidly secured behind a receiving plate 177 of the 60 main frame. The block 175 has a pin 178 which slidably engages in slot 179 in the lower end portion of a rod 180 which is pivoted to the arm 145 as at the point 146. Thus when the arm 145 is lifted, the rod 180 will engage the pin 178 65 to lift the lowering unit, but when the arm 145 is lowered the lowering unit will of course be free to move downwardly with the grid plate under gravitational action.

Extending from the block 175 are two outwardly extending bars 181 which at their outer ends support a pair of guide blocks 182 which are vertically movable in recessed standards at the sides of the main frame. Each of these blocks 182 has a right angular projection 183 disposed 70 in line with the upper end of the channel 162,

as shown in Fig. 9, but which may be moved so as to be in a receiving position with respect to the curved channel 163. Immediately under the extension 183 each block 182 is provided with a pivoted finger 184 yieldingly held in its upward position by a spring 185. The space between the members 183 and 184 is such that it will receive the adjacent ear of the grid plate when the latter is carried by the platen up to the vertical position, and when the platen then moves back to 10 its receiving position the jaw formed by the members 183 and 184 will yieldably retain the grid plate ear 164 until the plate is moved down sufficiently to become engaged by conveyor rollers, at which time such rollers will pull the plate down 15 to release it from the two fingers 184.

The lowering unit will move downwardly in synchronism with the lever arm 145 as controlled by the cam 111, which cam regulates the downward speed. However, this is not a positive downward feed, and consequently should the plate being moved downwardly come in contact with the plate immediately below it before the last mentioned plate will be cleared, then the pin and slot construction 178—179 will of course permit 20 the members 145 and 147 to move downwardly in synchronism with the cam movement, but will leave the lowering device sufficiently suspended 25 so that it may complete its movement under gravitational action and as fast as may be permitted 30 by the movement of the preceding interfering grid plate. As the grid plates move downwardly with the lowering unit they are first engaged by a pair of rollers 186 and 187, the first of which is journaled in a stationary lug 188 and the second of which is mounted for rotation in a movable lug extension 189 of a frame 190. The roller 186 has a shaft 191 extending to the outside of the frame work, and on its outer end is provided with a small pinion 192 as shown in Fig. 2, which 40 pinion is connected in a train of power driven gears, with a result that the roller 186 is at all times positively driven. However, it is not so much the purpose of this roller to create a feeding action to the plate as it is to insure that the 45 plate will not stop but continue the normal movement or speed which it maintains when leaving the lowering device.

As the plates leave the rollers 186 and 187 they come in contact with a pair of feed rolls 193 and 50 194, and it is the purpose of these rolls to impart a positive feeding action to the downwardly moving grid plates and at a predetermined speed, as will presently be described. It may here be noted, however, that the peripheral speed of the rolls 55 193 and 194 is somewhat slower than the normal action of the feeding action of the platen and lowering device, and the purpose of this difference in speed is to enable me to employ to advantage a gap preventing mechanism which will now 60 be described.

This mechanism includes the roller 187 and the frame 190, which frame is pivotally mounted as at 195 to the platen frame, and moves with it as the same is oscillated up and down. The upper 65 end of the frame 190, as shown in Fig. 9, is spring held away from the platen plate proper by a spring 196, which spring tends to urge the frame 190 toward a stop bolt 197, and thus also tends to urge the roller 187 toward the roller 186. The 70 frame 190 is further provided with a laterally extending stop arm 198 (see Figs. 3 and 9), which arm has for its purpose to contact under certain conditions with a lever arm 199 extending down from a shaft 200, which shaft is provided with 75

5 a second arm 201 in the lower end of which is mounted the bar 127. A pair of lock nuts 202 are secured upon the end of the shaft 127 whereby it may be adjusted with respect to the arm 201, and a spring 203 is mounted on the bar 127 to maintain proper working engagement as between the members 201 and 202. The shaft 200, as shown in Fig. 4, not only serves to support the levers 199 and 201, but also serves as a tie bar to rigidly connect the upper end of the guide plates 161.

10 The operation of the gap closing construction may be briefly described as follows: When a plate is delivered from the lowering device, as 15 already stated it becomes engaged between the rollers 193 and 194, and before the next succeeding plate can be delivered by the platen the plate first mentioned will probably reach the dotted line position shown immediately between 20 the rollers 193 and 194. However, as the rollers 193 and 194 have a slower feeding speed than the platen and lowering device, the result will 25 obviously be that under normal operation the platen and lowering device speeds will gradually catch up with the speed of the rollers 193-194; and as this gain is made the position of the last plate engaged by the rollers will gradually be at a higher level until the time 30 is reached when they will still be in contact between the rollers 186 and 187 when the next plate is ready for delivery by the platen. If the preceding plate is below the rollers 186-187 when the platen is raised to its vertical position, then the roller 187 will be moved to a 35 position in physical contact with the roller 186, and when this is done nothing will happen to the levers 199 and 201, because the spring 196 will maintain the upper end of the frame 190 in constant contact with the stop bolt 187; and 40 as long as this condition is maintained the clutch shown in Fig. 10 will maintain driving contact between the gear 49 and the shaft 50 at all times. However, when the last delivered plate 45 is so high that when the next upward movement of the platen is made, the roller 187, instead of reaching the roller 186, will contact with the grid plate intermediate the rollers, and thereupon will actuate the lever or frame 190 to move the upper end thereof away from the stop bolt 50 197, as shown in Fig. 9; and when this occurs the extension 198 will engage the lever arm 199 and move it sufficiently so that the corresponding movement transmitted to the lever 201 will act against the lock nuts 202, and thus give a short 55 pull on the rod 127; and this pull is sufficient to disengage the clutch and thus stop the platen and feeding mechanism. However, as soon as the grid plate has moved downwardly out of 60 contact with the rollers 186 and 187 the spring 196 will again restore the frame 190 to its original position, whereupon the clutch will again engage to restore the platen and lowering device movements.

65 Thus it will be seen that the mechanism will positively insure the plates being fed into the pasting mechanism not only at a uniform speed but with edge to edge contact so that there will be no space between the successive grid plates.

70 The roller 193 has a shaft which is journaled in the main frame of the machine and at one end is provided with a sprocket pinion 204 driven by an idler gear 205. The pinion 204 in turn drives an idler pinion 206 which meshes with the pinion 192 so as to positively rotate the roller 186. The feed roller 194 is also positively 75

actuated, being driven from the pinion 204 by a pinion 207 meshing therewith. The pinion 207 is mounted on one end extension of the roller 194, and this roller has corresponding end extensions at both ends which are journaled in 5 blocks 208 which are adjustably mounted for movement against cushioning springs 209, and are adjustable by set screws 210 to regulate the spacing as between the rollers 193 and 194. The purpose of the springs 209 is of course to permit the plates to pass through between the rollers even though they may carry with them some 10 obstruction or projection, and thereby prevent any damage to the rollers.

The idler gear 205 is driven by a gear 211 15 mounted on the shaft extension of a feed belt roller 212, which roller is in turn actuated by the feed belt 213 which passes over a roller 214 and over a large roller 215 at the rear part of the machine, and which roller 215 has the shaft 20 34 which is rotated in the manner previously described.

The gear 211 also meshes with and drives a gear 216 mounted on the shaft extension of a presser roller 217 which cooperates with the paste 25 belt 213 at a point opposite the roller 212. The shaft ends of the roller 217 are mounted in yieldable and adjustable supporting devices, one of which is shown in Fig. 2 and the other of which is indicated in Fig. 1 and by dotted lines 30 in Fig. 7. These devices each include a lever 218, mounted one each on the opposite ends of a shaft 219 which extends entirely through the carriage housing, as shown in Fig. 7. The lever 218 on the side of the machine shown in Fig. 2 35 is tiltably adjustable under the action of a pivoted rod 220 which extends through an oscillatable lug 221, and its tiltable movement is controlled under the action of a nut 222 which is threaded on the bolt and operates a channeled 40 collar 223 rotatable in the lug 221. At the end opposite from the bar 220 each of the levers 218 is provided with a link 224 which supports a bar 225, which bar is also slidably mounted in a bearing extension 226 of the lever 218. A spring 45 227 tends to push the bar rearwardly until it is stopped by an adjustable nut 228 contacting with the lug 226. The rear end of the bar 225 forms a bearing for the shaft extension of the 50 roller 217.

55 From the foregoing it will be seen that the springs 227 at the opposite sides of the machine will cause the roller 217 to be pressed toward the roller 215, but that the roller will be yieldable in substantially the same manner as roller 194 so that it can give under abnormal operating conditions. The purpose of the adjustment 220-223 is to provide means for vertically adjusting the roller 217 and without in any way interfering with the cushioning mechanism just 60 referred to. The object in vertically adjusting the roller 217 is to regulate the spacing between itself and a shoe 229 which extends transversely through the machine in spaced relation with a cooperating shoe 230 which is disposed immediately below the forward end of the belt 213, 65 as shown in Fig. 7.

70 It may here be noted that the two shoes 229 and 230 are rigid with respect to the main frame of the machine, but that the rollers 217, 194, and 187 are all movable in conjunction with the carriage unit 69. This is also true with respect to a roller 231 mounted below the shoe 229. An additional roller 232 cooperating with the roller 231 is, like the rollers 212, 193, and 186, journaled in 75

fixed relationship with respect to the main frame. The roller 231, as shown in Figs. 2 and 7, is yieldably supported as at 233, and is positively driven together with the roller 232 by gear pinions 5 234 and 235, respectively. The roller 232 is adjustably but not flexibly mounted in movable bearing blocks 236 controlled by a pair of lock nuts 237 engaging a fixed lug 238. The pinion 235 meshes with a pinion 239 which operates in 10 unison with a pinion 240, and both of these pinions 239 and 240 are mounted on a stub shaft 241. The pinion 240 meshes with the gear 211 and the purpose of the pinions 239 and 240 is to give proper direction to and to reduce the speed 15 of the rollers 231 and 232.

It may here be noted that a pair of spaced 20 guide plates 242 are arranged between the rollers 186-187 and the rollers 193-194, and that a similar pair of guide plates 243 are disposed 25 below the last mentioned rollers; and these pairs of guide plates have for their obvious purpose to properly direct the grid plates down through the respective feed and paste applying rollers.

As the downwardly moving grid plates are 30 discharged from in between the rollers 231 and 232 their outer lateral rim portions come into engagement with a pair of resistance units designated generally by the number 244, and one of which units as shown in enlarged detail in Fig. 8. These 35 units each include an arm 245 pivotally secured to the main frame as at 246 so that their opposite ends may be swung outwardly with respect to the frame. However, these arms 245 are normally rigidly secured to the frame by bolts 247 when the machine is in operation. At their forward ends the arms 245 are each provided with a fixed guide flange 248 and a yieldable guide flange 249, between which flanges is defined a narrow, vertical opening through which the marginal portions of the grid plates move. The flange 249 is supported at the inner end of a lever 250 which is pivoted to the arm 245 as at 251. A bolt 252 extends through the lever 250 to which it is adjustably secured as by nuts 253, and this bolt 252 is constantly under the tension of a spring 254 which connects the bolt to a portion of the arm 245, and this spring 254 has for its purpose to yieldably press the flange 249 toward the flange 248.

50 However, the members 245 and 250 are provided with stops 255 to limit this clamping tendency, and consequently the flanges 248 and 249 at no time come in physical contact with each other. The opening between the flanges is slightly tapered at its upper end so as to properly receive the downwardly moving grid plates.

As the successive plates are pressed downwardly through the units 244 they are delivered to a conveyor comprising a pair of chains 256 between 60 which the grid plates may drop, but upon which the projecting lugs 164 of the grid plates will stop and ride along on these conveyor chains. The purpose of the units 244 is to retard the drop of the grid plates as they pass from the rollers 65 231-232 to the conveyor chains so that the delivery to the chains will not be made under such conditions as may possibly injure the plates.

It has been stated that the flanges 248-249 are designed to engage the side rim portions of 70 the plates, but it may here be noted that it may be sufficient to so arrange the units 244 so that they will engage only the projecting lugs 164 of the grid plates. In this event the devices 244 will additionally serve to straighten out the grid 75 plates should one side drop from rollers 231-232

slightly in advance of the other side. Under such circumstances the grid plate lug first dropped will be held suspended between the flanges 248-249 until the opposite plate lug has dropped into engagement with the other device 244. When the next grid plate then moves down it will engage the plate in parallel edge to edge contact so that it will pass or be pushed down properly to the conveyor 256.

Disposed at a level immediately below the units 10 244 and one at each side of the machine, are a pair of pipes 257 provided with valves 258 and terminating at their ends immediately below the flanges 248-249 in nozzles 259. The purpose of the pipes 257 is to conduct steam, air or other 15 fluid under pressure to the nozzles 259, and these nozzles are so arranged that they will project a stream of air, steam, or other fluid against the outer edge extremities of the grid plates as they pass from the units 244 to the conveyor chain 256 20 to thereby clean such outer edges of the grid plates and remove the paste that may be adhering to these edges as the plates leave the pasting machine. This method is found to be highly preferable to brushes or other mechanical devices 25 for performing this function inasmuch as such brushes or devices will invariably become clogged up with the paste and require frequent cleaning. The fluid pressure from the nozzles 259 may of course be controlled or entirely shut off by the 30 valves 258 as circumstances may require.

Attention is now directed to the paste receptacle and paste applying mechanism as shown in Figs. 1, 2, 3, 5, and 6. The receptacle proper includes two side walls 260 integrally connected by a rear wall 261, and these three walls are provided at their upper edges with integral, flared flanges 262. The front wall 263 of the receptacle is mounted for slight vertical movement with respect to the side walls in conjunction with a paste feed roller 264. This feed roller is mounted on a shaft 265 which extends through a pair of slots 266 in the side walls 260, and is journaled at its ends in a pair of irregularly shaped levers 267 and 268, which levers are rigidly secured at their rear ends to a sleeve 269, which sleeve is trunnioned in a pair of rearwardly flanged extensions 270 of the receptacle wall 261. The levers 267 and 268 are provided with integral disc portions 271 which bear against the side walls 260 to prevent the paste material from leaking out through the slots 266. The upper end of the front wall 263 has a shaft 272 extending through and rigidly attached to the front wall. This shaft 272 extends through slots 273 in the side walls 260, and is journaled at its ends in the upper forward extremities of the levers 267 and 268.

The lower end of the front wall 263 is provided with lugs 274 (see Fig. 3), which lugs stop against the inner tapered ends of bolts 275, and by shimming the heads of these bolts as at 276 it will be seen that slight adjustments may be made between the lower end of the wall 263 and the roller 264. The purpose of this adjustment is to regulate the position of a plate 277 which is secured as at 278 to the lower end of the wall with respect to the roller 264. As seen in Fig. 6, this plate 277 has an arcuate inner edge which appears to be in contact with the roller 264, but which in fact is preferably very slightly spaced 70 from the roller so that it will not have frictional engagement therewith. The edge of the plate, however, is so close to the roller that it will remove all the paste therefrom as the roller rotates in the direction indicated by the arrow in Figs. 75

5 and 6. It will also be noted that the inner end 10 of the plate 277 is provided with a shoulder 279 which is spaced slightly from the belt or carrier 213, and it is the purpose of this shoulder to regulate the thickness of the paste film which is to be carried down with the belt and to the grid plates as they pass between the rollers 212 and 217.

The upper end of the wall 263 is provided with 15 a pair of lugs 280 between which is pivoted, as at 281, a rod 282 which extends up into a yoke 283 mounted upon the forward, upper edges of the paste receptacle. This yoke contains a spring 284 which tends at all times to hold the rod 282 downwardly. The rod 282 has a flange or washer 285 which extends under a finger 286 of an electric switch 287 which controls the circuit through wires 288 connected with the power line of the motor 25. This switch will of course be closed at 20 all times as long as the rod 282 is in its downward position. However, should the rod be raised against the tension of the spring 284, as would happen for instance when some object which had become mixed in the paste would come in contact 25 with the roller 264, or with the plate 277, as such an object might readily cause serious damage if not removed before it could reach the paste applying rolls, it is essential that the machine be stopped immediately before the object can reach 30 the rolls; and this contingency is provided for by the above described arrangement.

The shaft 265 of the roller 264 is provided at one end with a sprocket gear 289, which gear is driven by a sprocket chain 290 which also passes 35 over a sprocket gear 291 on a shaft 292 which is journaled in the sleeve 269. At its other end the shaft 292 has a gear 293 meshing with a gear 294 on a shaft 295 which is also journaled in the extensions 270 of the receptacle wall 261. The 40 shaft 295 is in turn driven from the shaft 34 by sprocket gears 296, sprocket chains 297, and sprocket gear 298.

It may here be noted that the sprocket chain 290 passes over an idler sprocket 299, which 45 sprocket is preferably adjustable on the arm 267 so that it may be employed to take up slack in or loosen the chain 290. The shaft 292 is further provided with a sprocket gear and chain connection 300 for driving a shaft 301 which is also 50 journaled at its ends in the arms 267 and 268, and passes through slots similar to 266 in the side walls of the receptacle so as to permit slight vertical oscillation of the frame arms. This shaft 301 is provided adjacent the inner faces of 55 the receptacle side walls 260 with disc like members 302 so as to prevent leakage of paste outwardly through these slots.

Intermediate the discs 302 the shaft 301 is provided with a curved feed blade 303, and it is 60 the purpose of this blade when rotated in the direction of the arrow, as shown in Fig. 5, to constantly keep urging the paste material into the tapering space between the roller 264 and the adjacent belt portion 213, thus insuring that 65 there will always be a sufficient and proper flow of paste into this recess.

The shaft 292 also operates still another mechanism within the paste receptacle, and this 70 is a pair of blades or arms 304 which are mounted 75 on a shaft 305 and have a vertical oscillating movement immediately adjacent to the inner surfaces of the walls 260 so as to prevent the paste from clinging or adhering to these surfaces and to thus insure the proper movement of the paste mass downwardly to the feed belt after the

receptacle has been supplied from time to time with the paste material which is dumped into the open top of the receptacle. The shaft 305 is provided at one of its ends with a rocker arm 306 connected by a pitman 307 to an eccentric pin 5 308 carried on a small disc 309 at the corresponding end of the shaft 295. Thus the rotary motion of the shaft 295 will be converted to an oscillating movement in the blades 304.

The roller 215 of the feed belt 213 is mounted 10 on the driven shaft 234, and in order that this shaft may be adjusted to thereby tighten or loosen the belt 213 the ends of the shaft are journaled in bearing blocks 310 which are slideable with respect to the side walls of the machine, and are connected for simultaneous adjustment by a beam 311, which beam, at a point intermediate its ends and between the upper and lower runs of the paste belt 213, is provided with a threaded bar 312 which screws into a member 20 313. This member is rotatably fixed in a bearing beam 314 and is provided with worm gear teeth 315 meshing with a worm 316, which worm terminates in a squared head at one side of the machine, as shown in Fig. 2, so that it may be 25 engaged by a wrench and turned to thus rotate the member 313, and consequently give the required adjustment to the paste belt 213. It may be noted that while the belt 213 may be made of any suitable material I prefer to use a 30 heavy woven fabric for this purpose.

The carrier chains 256 which receive the pasted grid plates from the units 244 are mounted on a pair of sprocket gears 317 carried by the driven shaft 44, and at the rear end of the machine these 35 chains 256 pass over pinions 318 secured on stub shafts 319, which stub shafts are sufficiently short so as to permit the body portions of the grid plates to pass between them. As the plates riding upon the chains 256 pass over the centers of 40 the pulleys 318 they are guided by thin, laterally arranged guide plates 320 so that the ears or lugs 164 of the plates will drop down upon the forward ends of a pair of levers 321 which are 45 respectively pivoted as at 322 to bracket extensions 323 of the main frame 21, as indicated in Fig. 11.

Springs 324 are arranged to hold the forward ends of the levers 321 up in operative position against stop pins 325. The lower ends of the 50 levers 321 are provided with hooks 326 for releasably engaging pins 327 fixed in arms 328 extending forwardly from a shaft 329 also journaled in the bracket 323. The arms 328 are shown as bifurcated at their forward ends with the depending portions of the levers 321 operating between the forward portions of the arms. The arms 328 are keyed to the shaft 329 and are 55 yieldingly held upwardly by a spring 330. As the levers 321 are independently mounted they are of course independently actuated, and not necessarily at the same time by the grid lugs 164. However, the arms 328 being both keyed to the shaft 329, must operate simultaneously; and consequently they cannot drop or be lowered against 60 the tension of the spring 330 and under the weight of the grid plate until the latch levers 321 at opposite sides of the machine have both been released. The purpose of this arrangement is to insure that the grid plates will be fed into the 65 reroll mechanism with their lower edges in a correct horizontal position, and with their side edges vertical. It is of course important that the plates be fed properly into the reroll device so that they can travel and be manipulated properly, both in 70 75

passing through the reroll mechanism and also to the conveyor belt to which they are subsequently delivered.

As the plates are delivered downwardly by the arms 328 they come into contact with a pair of reroll belts 331 and 332. The first of these belts passes over a roller 333 carried by the driven shaft 65, and also passes over a pair of relatively smaller rollers 334 and 335, and between these two rollers 334 and 335 is disposed a shoe 336 which projects slightly beyond the rollers and has a curved face over which the apron 331 will travel. This shoe has a chamber 337 supplied by a conduit 338, and the chamber 337 in turn communicates with the apron contacting face of the shoe through a series of perforations 339. The tension of the apron or belt 331 may be controlled by turning a worm screw 340, which in turn meshes with and drives a worm gear 341, which gear is rotatably mounted in a cross beam 342, and is internally threaded to receive a threaded bar 343 which in turn operates a bearing block 344 in which the shaft 65 of the roller 333 is mounted. The apron or belt 332 passes over a roller 345 mounted on the driven shaft 61, and this apron also passes over rollers and a shoe and includes an adjusting mechanism similar to that which has been described in connection with the apron 331; and consequently the corresponding parts 30 are similarly designated.

The conduit 338 is controlled by a valve 346, and it is the purpose of this conduit to transmit hot air or steam to the grid contacting areas of the belts 331 and 332; and by blowing or forcing 35 hot air or steam through the belts at this point, I eliminate all possibility of having the paste carried by the grids adhere to the belts, and thus permit the belt surfaces to serve their proper and sole function of giving or imparting to the grid 40 plates a complete finishing treatment.

The reroll mechanism which includes the belt 331 may be designated generally by the numeral 347, and this unit remains in a fixed position with respect to the main frame 20 of the machine. 45 The reroll mechanism which includes the belt 332, may be designated generally by the numeral 348, and this unit is mounted for yieldable movement with respect to the unit 347 in the following manner:

50 The unit includes a frame 349 in which the rollers and other parts are mounted, and the frame 349 is in turn movably supported upon the frame extension 23 by a pair of links 350 and 351 at one side of the machine and by a link 352 at the other side of the machine. The links 350 and 351 are pivotally secured to the extension 23 as at 353, while their upper ends are pivotally secured to the frame 349 as at 354. The link 352 is similarly pivoted at the other side of 55 the machine to the members 23 and 349, and moves in parallelism with the links 350 and 351.

The unit 348 is yieldingly pressed toward the unit 347 by a spring 355 which connects an upper extension of the link 351 with the main frame of 60 the machine. It is not desired, however, to at any time have the units so close together that the belts 331 and 332 will have physical contact with each other, and consequently I provide an adjustable stop screw 356 for contacting with the link 351; and this screw may be adjusted to control the spacing as between the two reroll belts. It 65 may here be noted that the roller 335a of the unit 348 is driven by the belt 332, and in turn is provided at one end with a sprocket gear 357 which 70 operates through a sprocket chain 358 and a

sprocket gear 359 to rotate a feed roller 360 journaled in the frame extension.

Cooperating with the roller 360 is a roller 361 mounted in a lever 362 which fulcrums as at 363 and is actuated by a spring 364 to press the roller 361 toward the roller 360. The rollers 360 and 361, as shown in Fig. 13, are comparatively narrow, and it is only intended that they should engage the comparatively heavy bar portion that runs down centrally through a grid plate of the 10 double unit type, as indicated in Fig. 3. It may here also be observed that the roller 360 is connected to the sprocket pinion 359 by a shaft 365 which is journaled in a projecting arm 366 of the frame extension 23. As the grid plates leave the 15 reroll belts 331 and 332 they are further guided, and particularly before they enter between the rollers 360 and 361, by upstanding pairs of guide arms 367 which are spaced so as to receive the grids as indicated in Figs. 11, 12 and 13. 20

As the grid plates leave the reroll mechanism and are delivered to the conveyor below, it is necessary, however, to provide further means for controlling their movements and particularly to prevent any possibility of transverse tilting of the 25 plate and to maintain it in proper vertical alignment so that it will pass properly down into the conveyor; and to this end I have provided a control mechanism which includes a pair of levers 368 which are pivoted as at 369 to bracket arms 370, 30 and are further provided with link connections 371 which connect with levers 372 also fulcrumed to the bracket 370. The forward ends of the levers 372 are yieldably held down against adjustable set screws 373 by springs 374, which springs 35 will thus serve to yieldably hold up the rear or inwardly bent ends of the levers 369. These inwardly bent ends, as shown particularly in Figs. 13 and 14, are so arranged that they will engage under the grid lugs 164; but as the grids are pulled 40 down by the roller 360 the lever arms 368 will of course yield downwardly until the lugs are entirely disengaged, whereupon the spring 374 will again raise the levers 368 to their normal receiving position. 45

The bracket arms 370 are adjustable vertically in conjunction with the vertical adjustment, presently to be described, for the forward end of the conveyor unit which receives the grid plates from the reroll mechanism. This conveyor unit includes a pair of chains 375 which pass over forward sprocket gears 376 and over relatively smaller sprocket gears 377 at the rear end of the frame extension 23. The sprocket gears 376 are secured on a shaft 378 which is journaled in a 50 sleeve 379 formed integrally with a block 380 mounted for vertical adjustment in the crossbeam 22. The block 380 is raised and lowered by an arm 381 secured on a shaft 382, and the end of 55 which shaft is squared as at 383 so that a socket wrench may be applied thereto. After the adjustment has been made the block 380 is firmly secured in place by a clamping shaft 384 which extends through a portion of the block 380, and is threaded into an adjacent portion of the cross beam 22 so that when a wrench is applied to the square end 385 of this bar, a shoulder 386 will firmly clamp the block 380 between itself and the adjacent portion of the cross beam 22. This bar 60 384 must of course be loosened before the lift arm 381 may be moved either up or down. 65

The shaft 378 is provided at one end with a spur gear 387 which meshes with a gear 388 on the inner end of the shaft 58, which shaft, 75

through the worm gear 57, receives power from the worn 56 as previously described.

It may be noted that the vertical movement of the block 380 will slightly change the distance between the centers of the gears 381 and 388, but this change is so slight that it will not interfere with the proper intermeshing and driving connections established by these gears. It may here also be noted that the primary purpose of this adjustment is to provide proper clearance for the tops of the grid plates as they travel along on the upper run of the chains 375 when grid plates are being pasted that have the lugs 164 spaced from the upper corners of the grid plates; for under such circumstances the plates will require greater spacing as between the conveyor 375 and the reroll unit 348. The conveyor chains 375 travel at a comparatively low rate of speed, and consequently the plates will be delivered to this conveyor in comparatively close proximity to each other, as indicated in Figs. 5 and 11. As the plates are successively placed upon the conveyor chains 375 they are carried rearwardly toward and between the sprocket pinions 377, and as they reach this extremity of the conveyor unit the grid lugs come in contact with the peripheries of a pair of thin metal plates 389, which plates are mounted on stub shafts 390 journaled in the frame extensions 23; and each of these stub shafts 390 receives motion from the stub shaft 391 of the pinions 377 through a train of speed increasing gears 392; which gears are substantially enclosed within chambered out portions of the frame extension members 23. Thus the disc plates 389, traveling at a comparatively greater rate of speed, will successively remove the grids from the conveyor chains 375 and thus deliver them from the machine. As indicated in Fig. 15, there is full clearance between the plates 389 for the main body portions of the grid plates; and as the grid plates are discharged from the plates 389 they may be either manually taken from the machine and stacked up or they may be received by still another conveyor (not shown) for delivery to another location where the plates are to be further treated or made use of for commercial purposes.

While the operation of the machine will no doubt be understood from the foregoing description, a brief résumé may be made as follows:

Assuming that a stack of grid plates has been placed between the holders 93 and that the paste chamber is sufficiently supplied with material, the motor 25 is started and operates through the various driving mechanisms that have already been described, to set the various parts in motion. The stripper plate 95 is reciprocated back and forth by the cam and lever mechanism to successively remove the plates from the bottom of the stack and 55 advance them, one at a time, to the platen 155 where they are engaged by the retarder or spring arm 167. This member has for its purpose to hold the plates in place and to prevent them from being moved too far rearwardly so as to injure 60 the projecting grid plate lugs, or cause them to go beyond the point where they may be properly started up through either one of the pair of channels 162 or 163. As soon as they are properly placed upon the platen 155, the latter oscillates or moves upwardly to the vertical position, 65 placing the lugs of the grid plates in the jaws 183—184 of the lowering device. Upon being so received, the lowering device moves downwardly while the platen is being returned to its initial 70 position to receive another plate from the strip-

per mechanism. The plates then travel down between the rollers 186—187, the guide plates 242, and into the primary feed rolls 193 and 194, always of course maintaining their proper alignment with respect to each other. The 5 primary feed rolls then move the grid plates successively down between the guide plates 243 and into the pasting mechanism.

It is essential that the plates move into and through the pasting unit in close proximity to 10 each other, and for this reason the feed and pasting rolls travel at a slightly lower rate of speed than the feeding speed of the stripper, platen, and lowering units. Consequently when the vertical series of plates passing into the pasting 15 rollers builds up to a certain point, the last of such series will remain engaged by the rollers 186 and 187, and when this occurs the position of the roller 187 will operate through the mechanism shown in Figs. 9 and 10 to stop the stripper, 20 platen, and lowering device momentarily, or until the last of such plates passes through and entirely out of contact with the roller 187, at which time the first mentioned feeding devices will be again 25 put in action. Thus it will be seen that there will be no gaps of any consequence between any two grids passing down into the pasting mechanism, and that they will at all times retain proper feeding alignment with respect to each other.

As the grid plates travel through between the 30 guide bars or plates 243 they come into contact with the feed belt 213 and the compression roller 217 which operates in conjunction with the feed belt roller 212. The film or layer of paste is applied to the grid plates at this point, and is 35 pressed into so as to thoroughly fill all of the spaces or interstices in the respective grid plate units. The paste is carried to this point by the belt 213 which receives its supply from the paste container or receptacle. This paste, being of a 40 rather heavy consistency, requires careful and proper feeding action if it is to be efficiently spread over the entire surface of the belt, and to this end I have provided various devices including the belt itself, and roller 264, and a feeding 45 mechanism 303. The oscillating scraper arms 304 are not essentially paste feeding devices except insofar as they tend to prevent the paste mass from sticking to the side walls of the receptacle. The roller 264 operates in a clockwise 50 direction, as shown in Figs. 5 and 6, and in doing so cooperates with the belt action to reduce the paste bulk into a relatively thin layer of material. The device 303, while having some agitating effect on the paste, is primarily intended to 55 merely urge the paste into the tapered recess formed by the belt and the roller 264.

The plate 277 (see Fig. 6) is mounted for very slight contact with the roller 264, and has for its purposes, first, to separate the paste film from 60 the roller so that it will not be carried back into the paste receptacle, and second by virtue of the shoulder 279 to further limit and define the exact desired thickness of the paste film before it is carried down over the inclined surface of the 65 belt to the rollers 212—217.

Should any object other than paste by any chance find its way into the paste receptacle, it will, if sufficiently large to do any damage, find its 70 way into the space between the roller 264 and belt 213, and when this occurs the roller, as well as the plate 277, will be lifted as provided for by the movability of the arms 267 and 268, and this movement will be carried through the front wall 75

263 of the receptacle and through the bolt 282 to the member 285 which will, by lifting the switch arm 286, break the switch 287 and thus open the circuit 288 to the motor 25, and consequently immediately stop the motor and the running of all parts of the machine. It may at this time also be noted that the various mechanisms which operate through the device shown in Figs. 9 and 10 will also function through the drive release action of the members 114 and 115 to shut off the grid plate feeding devices should any jam occur in this part of the machine.

With respect to the paste feeding mechanism, it may here also be noted that provision is made for readily removing and replacing the feed belt 213 should it become worn or injured to the extent that replacement should be required. To this end I have mounted the belt rollers 212, 214, and the beam 311 of the shaft 34 in a carriage 393 which is longitudinally slidable in the main frame 20 of the machine, and is preferably gibbed in the manner that the carriage 69 is shown to be gibbed to the main frame 20 in Fig. 2A. When the carriage 393 has been placed in operative position I extend through it a removable cross bar 394, and this cross bar is arranged to contact within the carriage with the cross beam 314. One end of the cross bar is pivotally secured to the main frame of the machine, as shown at 395 in Fig. 1, while at its other end, as shown in Fig. 2, the cross bar contacts with a set screw 396, and by adjusting this set screw the carriage 393 may be slightly moved so as to adjust the feeding end of the belt 213 with respect to the other relatively fixed parts of the machine. It will thus be seen that when it is desired to replace or repair the belt 213 it is only necessary to remove the cross bar 394, and the drive chain 297, whereupon the belt supporting structure may be removed as a unit, and after necessary repairs or adjustments have been made, may be replaced in a like manner.

The roller 217 cooperates with the roller 212 to firmly press the paste into the grid plates from both sides, and while the roller 217 is mounted for slight flexing action under the resistance of the spring 227 it maintains a normally fixed position; and this position may be adjusted without interfering with the spring arrangement by turning the nut 222 which will operate through the rod 220 and lever 218 to give the desired adjustment.

As the paste supplied plates travel down between the shoes 229 and 230, any excess amount of paste that passes the roller 217 will tend to accumulate on the shoe 229, and if not carried down between the shoes will ordinarily pass between the shoe 229 and roller 217, and drop upon the roller 231, or over this roller, so as to pass down upon the hopper plate 81. The rollers 231 and 232 have for their object to wipe off any excess amount of paste that may still be adhering to the plates, and this they do by virtue of the slow, rubbing action which they produce on the plates. In other words, while these rollers operate in the same direction of travel that the plates have, they rotate at a very much lower rate of speed, and consequently will have the relative rubbing effect referred to.

As the plates leave the rollers 231—232 they are engaged by the retarder units 244, the purposes of which are to prevent the grid plates from dropping down too abruptly to the carrier chains 256, and to straighten out any plates which may

not have been properly discharged from the rollers 231—232. As the plates travel this part of their total course they are treated by the action of jets of steam or air projected by the nozzles 259, and as controlled by the valves 258. The nozzles 259 are so arranged that they will project the jet of air or steam against the outer vertical edges of the grid plates, and by doing so will remove any particles of paste that may be adhering to these edges. The plates are now carried by the conveyor 256, as shown in Fig. 5, to the reroll mechanism, and as they reach the end of the conveyor they are successively received by the latch members 321, and as soon as both of these latch members are engaged to thus insure proper position of the plate it is let down by the arms 328 into the reroll unit. This unit, as has already been set forth in detail, includes a pair of cooperating belts 331 and 332 which, at their plate engaging areas of contact travel over a pair of opposed shoes 336, and have sliding frictional contact with these shoes. The shoes are provided with chambers 337 which communicate with the belt contacting surfaces of the shoes through a plurality of perforations 339; and it is the object of these perforations to transmit steam or air supplied under pressure by the pipe 338 to the belts 331 and 332 at their points of contact with the grid plates; and it is the purpose of this provision to prevent the paste from adhering to the belts, particularly at this point, and which would or might otherwise occur, thus not only damaging the grid plate unit as such, but also interfering with the efficiency of the belt surface. It is found that by moving the belts over a perforated surface so as to thus receive fluid treatment, that the pressure set up by the fluid, be it air or steam, prevents any possibility of a vacuum or partial vacuum to thus attract the paste to the belt; and also, by so treating the belt leaves it in such a condition that it will not have a surface that the paste will tend to stick to.

It may here be noted that these belts 331 and 332 are preferably made of a heavy canvas or fabric material that has a noticeably rough or checked surface so that as it engages the exposed paste surface of the grid plates it will correspondingly roughen or corrugate such surface and thereby increase the effective exposed surface to correspondingly render the grid plate more efficient when it is ultimately placed in a battery.

After the plates have been subjected to the re-rolling treatment they pass downwardly between the guide arms 367 to the conveyor 375, and while so passing are arranged and maintained in proper position by the members 368—374, which cooperate to at all times maintain proper position of each plate as it leaves the reroll mechanism and is deposited upon the chains 375. As the plates are now carried rearwardly to the extreme end of the machine they are engaged by the peripheries of the thin disc plates 389 from which they may be transmitted to still another conveyor or be stacked up and carried away until they are to be used.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. In a grid pasting machine, means for supporting the grids in substantially horizontal positions, means for applying paste to the grids, pri- 75

mary and secondary conveying mechanisms for successively engaging the grids to tilt them into vertical positions and then advance them downwardly into applying means, means for driving 5 said conveying mechanisms at different rates of grid advancing speeds, said mechanisms each having means for positively engaging the grids so that the grids will travel at the conveying speeds of the respective mechanisms while thereby engaged, and means for intermittently disconnecting the driving means of the faster operated conveying mechanism so that its effectual grid advancing speed will correspond to that of the slower operated mechanism.

10 2. In a grid pasting machine, means for applying paste to the grids, primary and secondary conveying mechanisms for successively engaging the grids to advance them to the applying means, said mechanisms each having means for positively engaging the grids so that the grids will travel at the conveying speeds of the respective mechanisms while thereby engaged, means for operating the primary conveying mechanism at a higher rate of speed than the secondary mechanism, and means, responsive to the position of a 15 grid engaged in the secondary conveying mechanism, for disconnecting the operating means and thereby interrupting the normal speed of the primary conveying mechanism, said primary conveying means comprising a stack stripper, an oscillatable platen and a vertical carrier; and said secondary conveying mechanism comprising horizontally spaced rollers defining a vertical passageway therebetween for the grids.

20 3. In a grid pasting machine, means for applying paste to the grids while disposed in a vertical passageway, primary and secondary conveying mechanisms for successively engaging the grids to advance them into and downwardly through the passageway to the applying means, said mechanisms each having means for positively engaging the grids so that the grids will be supported and travel at the conveying speeds of the respective mechanisms while thereby engaged, means for operating the primary conveying mechanism at a higher rate of speed than the secondary mechanism, and means, actuatable by 25 the last of a series of grids passing from primary to secondary conveying mechanisms, for intermittently disconnecting the operating means and interrupting the relatively faster primary conveying mechanism speed and thereby retarding the grid conveying capacity thereof.

30 4. In a grid pasting machine, means for applying paste to the grids, primary and secondary conveying mechanisms for successively engaging the grids to advance them downwardly through a vertical passageway to the applying means, said mechanisms each having means for positively engaging the grids so that the grids will travel at the conveying speeds of the respective mechanisms while thereby engaged, means for actuating the primary conveying mechanism at a higher rate of speed than the secondary mechanism, and means, responsive to the position of a grid engaged in the secondary conveying mechanism, for intermittently rendering inoperative the actuating means of the primary mechanism, said secondary conveying mechanism comprising a pair of horizontally spaced power driven 35 rollers, and a pair of spaced guide bars adjacent the rollers and cooperating therewith to form the grid passageway.

40 5. In a grid pasting machine, means for applying paste to the grids, primary and secondary

feeding mechanisms for conveying grids to the applying means, said primary means including an oscillatable platen for converting the grids from substantially horizontal to substantially vertical position, and a lowering device for actuating the grids while in substantially vertical position down into the secondary feeding mechanism.

5 6. In a grid pasting machine, a pasting device, means for supporting a stack of unpasted grids, a platen mounted for oscillation between substantially horizontal and vertical positions, means for transferring a grid from the stack to the platen when the latter is in its substantially horizontal position, and means for removing the grid from the platen when the latter is in its substantially vertical position and for actuating said removed grid down into the pasting device.

10 7. In a grid pasting machine, a pasting device, means for supporting a stack of unpasted grids, a platen mounted for oscillation between substantially horizontal and vertical positions, means for transferring a grid from the stack to the platen when the latter is in its substantially horizontal position, friction means for controlling the movement of the grid being received on the platen, and means for receiving the grid from the platen, when the latter is raised, and delivering the grid to the pasting device.

15 8. In a grid pasting machine, a pasting device, means for supporting a stack of unpasted grids, a platen mounted for oscillation between substantially horizontal and vertical positions, means for transferring a grid from the stack to the platen when the latter is in its substantially horizontal position, means for engaging the grid to guide it to proper vertical feeding position as the platen is raised, and means for receiving the grid when in such vertical position and conveying it to the pasting device.

20 9. In a power operated grid pasting machine, means for feeding a series of grids through a paste applying zone, a paste receptacle having its bottom formed by an endless belt adapted to convey a layer of paste to said zone of paste application to the grids, a device cooperating with the belt to define the thickness of the paste layer, and means rendered operative by an abnormal spread between the paste layer thickness defining devices for stopping the machine.

25 10. In a grid pasting machine, means for conveying the grids vertically and in edge to edge series, a paste receptacle having its bottom defined by the surface of an endless belt traveling therethrough and adapted to carry a layer of paste and apply it to vertical faces of the grids at a point removed from the paste body in the receptacle, and means, other than gravity, for urging the paste in the receptacle into contact with the belt surface.

30 11. In a pasting machine, a paste receptacle, a conveyor unit mounted under the receptacle and comprising a frame, rollers mounted in the frame, and an endless belt carried by said rollers, said belt having its upper run extending through the bottom of the receptacle and forming a support for the paste material therein, and means for releasably securing said frame in the machine so that said unit may be bodily removed from normal operating position and thereby facilitate replacement or repair of the belt.

35 12. A mechanism for rerolling pasted grids comprising a pair of roller mounted power driven belts, a pair of parallel shoes extending

- transversely of and within the respective belts, said shoes having opposed rounded portions over which the belts pass and between which portions the grids are engaged by the belts to produce the 5 rerolling action, said shoes having openings for the discharge of fluid to the belts as the belts pass the zones of contact as between the belts and the opposite grid surfaces.
13. In a machine of the character described, 10 a grid plate treating device, a conveyor for conveying the plates in a horizontal direction to a delivery position above the treating device, means for receiving the plates from the conveyor and releasing them to the treating device, said 15 receiving and releasing means comprising a pair of members engageable with opposite sides of the grid plates and simultaneously movable downwardly to maintain proper feeding position of the plates as they pass to the treating device, means 20 for yieldably holding the pair of members raised, and grid plate actuated devices, one at each side of the conveyor, for releasably securing the pair of members in raised position.
14. In a grid pasting machine, means for supporting a stack of grids, an oscillatable platen adjacent the lower end of said supporting means, 25 means for successively stripping the grids from the bottom of the stack and placing them upon the platen when the latter is in a substantially horizontal position, a pasting mechanism, and means for successively removing the grids from the platen, when the latter is in a raised position, and delivering the grids to the pasting mechanism.
15. In a grid pasting machine, means for supporting a stack of grids, an oscillatable platen adjacent the lower end of said supporting means, 30 means for successively removing the grids from the stack and placing them upon the platen when the latter is in a substantially horizontal position, a pasting mechanism, and means for successively removing the grids from the platen, when the latter is in a raised position, and delivering the grids to the pasting mechanism.
16. In a grid pasting machine, a support and vertical guides for a stack of grids, a platen adjacent the support and oscillatable between lower, receiving, and upper discharging positions, a reciprocating stripper device for engaging the 35 lower end of the grid stack to successively remove the grids therefrom and place them on the platen when the latter is in its receiving position, a pasting device, and means for directing the grids discharged from the platen, when the latter is in its upper position, to the pasting mechanism.
17. In a grid pasting machine, a support and vertical guides for a stack of grids, a platen adjacent the support and oscillatable between 40 lower, receiving, and upper discharging positions, a reciprocating stripper device for engaging the lower end of the grid stack to successively remove the grids therefrom and place them on the platen when the latter is in its receiving position, a pasting device, and means for directing the grids discharged from the platen, when the latter is in its upper position, to the pasting mechanism, said guides being recessed at their lower ends to permit the passage therethrough of grids to 45 the platen.
18. In a grid pasting machine, a support and vertical guides for a stack of grids, a platen adjacent the support and oscillatable between lower, receiving, and upper discharging positions, a reciprocating stripper device for engaging the 50 lower end of the grid stack to successively remove the grids therefrom and place them on the platen when the latter is in its receiving position, a pasting device, and means for directing the grids discharged from the platen, when the latter is in its upper position, to the pasting mechanism.
19. In a grid pasting machine, an oscillatable platen movable from a substantially horizontal 55 grid receiving position to a substantially vertical grid discharging position, a pasting mechanism for receiving and applying paste to the grids as they are successively discharged from the platen, and means for intermittently supplying grids to the platen.
20. In a grid pasting machine, an oscillatable platen movable from a substantially horizontal grid receiving position to a substantially vertical grid discharging position, a pasting mechanism 60 for receiving and applying paste to the grids as they are successively discharged from the platen, and arcuate guides disposed laterally with respect to the platen for positioning the grids thereon as the platen is moved from horizontal to vertical position.
21. In a grid pasting machine, an oscillatable platen movable from a substantially horizontal grid receiving position to a substantially vertical grid discharging position, a pasting mechanism 65 disposed below the platen, and a lowering mechanism for receiving the grids as they are discharged from the platen and for directing them downwardly into the pasting machine.
22. In a grid pasting machine, an oscillatable platen movable from a substantially horizontal grid receiving position to a substantially vertical grid discharging position, a pasting mechanism disposed below the platen, and a lowering mechanism for receiving the grids as they are 70 discharged from the platen and for directing them downwardly into the pasting machine, said lowering mechanism including a vertically reciprocating carrier having releasable grips for engaging portions of the platen discharged grids.
23. In a grid pasting machine, a pasting device, means for feeding grids to the pasting device at a predetermined rate of speed, an oscillatable grid carrier for supplying grids to the feeding means, a roller carried by and oscillatably movable with the carrier for movement into and out of the path of grid travel, said roller being disposed in the path of grid travel when the carrier is in its discharging position, and operative connection 75 between the roller and the power mechanism for the carrier to control the frequency of carrier oscillations and thereby the grid feeding speed of the carrier to the feeding means.
24. In a grid pasting machine, a pasting device, power actuated means for feeding grids vertically to the pasting device, a power actuated oscillatable platen for receiving grids in a substantially horizontal position and tilting them to the vertical for transfer to the feeding means, a roller carried by the platen and movable therewith for traversing the path of vertical grid travel, and means responsive to grid contact with the roller for discontinuing the normal grid feeding action of the platen during the period of grid contact 80 by said roller.
25. In a grid pasting machine, a pasting device, power actuated means for feeding grids downwardly into the pasting device, a platen tiltably mounted adjacent the upper end of the feed- 85

- ing means for supplying grids thereto, a roller carried by the platen and disposed, when the platen is in grid discharge position, in the path of grid travel in the feeding means, means for transmitting power to oscillate the platen, and means responsive to grid contact with said roller for effectively disconnecting the power transmitted to the platen.
26. The combination in a grid pasting machine having a pasting mechanism and feed means for feeding grids vertically to the pasting mechanism, of a platen oscillatably mounted at the receiving end of the feed means for converting grids from non-vertical to vertical position, and means for removing the grids from the platen and directing them into the feed means.
27. The combination in a grid pasting machine having a pasting mechanism and feed means for feeding grids vertically to the pasting mechanism, of a platen oscillatably mounted at the receiving end of the feed means for converting grids from non-vertical to vertical position, a contact member mounted on and movable with the platen for contact with vertically moving grids when the platen is in its vertical position, and means influenced by said contact member for controlling the application of power to the platen to thereby regulate the grid feeding speed thereof.
28. In a grid pasting machine, means for feeding a series of grids through a paste applying zone, a paste receptacle, a device for conveying a layer of paste from the receptacle to the zone of paste application to the grids, a member cooperating with said device to define the thickness of the paste layer, and means operative by an abnormal spread between said device and member for stopping the conveying device.
29. In a grid pasting machine, means for feeding a series of grids through a paste applying zone, a paste receptacle, a device for conveying a layer of paste from the receptacle to the zone of paste application to the grids, a roller spaced from the device to define the thickness of the paste layer, and a blade associated with the roller surface to insure removal of the paste layer therefrom.
30. In a grid pasting machine, a paste receptacle having its bottom defined by the surface of an endless belt traveling therethrough and adapted to carry a layer of paste for application to the grids at a point removed from the paste body in the receptacle, a pair of oscillating scrapers movable adjacent the inner surfaces of the side walls of the receptacle to free the paste mass from adherence thereto, and means operative in said paste mass for urging the same into contact with the belt surface.
31. In a grid pasting machine, a paste receptacle having its bottom defined by the surface of an endless belt traveling therethrough and adapted to carry a layer of paste for application to the grids at a point removed from the paste body in the receptacle, a pair of oscillating scrapers movable adjacent the inner surfaces of the side walls of the receptacle to free the paste mass from adherence thereto, and means operative in said paste mass for urging the same into contact with the belt surface, said urging means being yieldably supported in the receptacle.
32. A grid plate pasting machine comprising a pair of power driven feed rollers for engaging the plates and moving them downwardly therebetween, pairs of spaced transversely arranged stationary guide bars disposed one pair above and the other pair below the rollers and having parallel opposed faces cooperating therewith to form a grid plate passageway, means for feeding grid plates end to end down into the upper guide bars, and means below the lower guide bars to apply paste to the plates as they are discharged therefrom, one of each of the pairs of rollers and guide bars being adjustable horizontally with respect to the other to regulate the size of the passageway.
33. A grid plate pasting machine comprising upper and lower pairs of power driven rollers and stationary guide bars cooperatively associated therewith to define a grid plate passageway, said rollers and guide bars being disposed transversely of the passageway and the rollers having gripping engagement with the opposite plane faces of the plates, and a belt passing over one of the rollers to convey paste to the grids while advancing through the passageway.
34. In a grid plate pasting machine, pairs of rollers and pairs of guide bars alternately arranged in vertical series to form a grid plate passageway, and extending transversely of the passageway, with the rollers and guide bars of each pair respectively engageable with opposite faces of the plates, and means for applying paste to the plates as they advance through the passageway.
35. In a grid plate pasting machine, pairs of rollers and pairs of guide bars alternately arranged in vertical series to form a grid plate passageway, and extending transversely of the passageway with the rollers and guide bars of each pair respectively engageable with opposite faces of the plates, means for rotating the rollers to advance the grid plates, and means for applying paste to the plates as they advance through the passageway.
36. In a grid plate pasting machine, pairs of rollers and pairs of guide bars alternately arranged in vertical series to form a grid plate passageway, and extending transversely of the passageway, with the rollers and guide bars of each pair respectively engageable with opposite faces of the plates, a belt passing over one of the rollers to convey paste to the grids advancing through the passageway, and means for advancing the plates.
37. In a grid plate pasting machine, a plate passageway defined in part by a pair of power driven rollers disposed transversely of the passageway and for engagement with opposite faces of the plates to advance them through the passageway, and a belt passing over one of the rollers to convey and apply paste to the grids passing between the rollers.
38. In a grid plate pasting machine, a plate passageway defined in part by a pair of power driven rollers disposed transversely of the passageway and for engagement with opposite faces of the plates to advance them through the passageway, a paste receptacle spaced with respect to the passageway, and a belt for conveying paste from the receptacle and applying it to the grids advancing through the passageway.
39. In a grid plate pasting machine, a plate passageway defined in part by a pair of power driven rollers disposed transversely of the passageway and for engagement with opposite faces of the plates to advance them through the passageway, a paste receptacle spaced with respect to the passageway, and a belt for conveying paste from the receptacle and applying it to the grids advancing through the passageway, said belt

passing through the bottom of the receptacle so as to support the paste therein.

40. In a grid plate pasting machine, a plate passageway defined in part by a pair of power driven rollers disposed transversely of the passageway and for engagement with opposite faces of the plates to advance them through the passageway, a paste receptacle spaced with respect to the passageway, a belt for conveying a continuous layer of paste from the receptacle to the plates in the passageway, and means for adjusting the thickness of the paste layer.

41. In a grid plate pasting machine, a plate passageway defined in part by a pair of rollers disposed transversely of the passageway and at opposite sides of the plates to grip and advance the plates when the rollers are rotated, intermeshing gears connecting the rollers for rotation in opposite directions, and a power driven belt passing over one of the rollers to supply power thereto and to convey paste to the plates passing between the rollers.

42. In a grid plate pasting machine, a plate passageway defined in part by a pair of rollers disposed transversely of the passageway and at opposite sides of the plates to grip and advance the plates when the rollers are rotated, intermeshing gears connecting the rollers for rotation in opposite directions, a belt passing over one of the rollers to convey paste to the plates passing between the rollers, and means for driving the rollers and belt.

43. In a grid plate pasting machine, a plate passageway defined in part by a pair of rollers disposed transversely of the passageway and at opposite sides of the plates to grip and advance the plates when the rollers are rotated, intermeshing gears connecting the rollers for rotation in opposite directions, a belt passing over one of the rollers to convey paste to the plates passing between the rollers, means for operating the rollers and belt, and a mounting for one of the rollers yieldably urging it toward the other roller.

44. In a grid plate pasting machine, a plate passageway defined in part by a pair of rollers disposed transversely of the passageway and at opposite sides of the plates to grip and advance the plates when the rollers are rotated, intermeshing gears connecting the rollers for rotation in opposite directions, a belt passing over one of the rollers to convey paste to the plates passing between the rollers, means operative to adjust the rollers with respect to each other to adjust the opening of the passageway without interrupting the driving engagement between said intermeshing gears, and operative to further open the passageway and disconnect the gears.

45. In a grid pasting machine, a passageway for the movement of grids therethrough, a paste receptacle, a roller adjacent the passageway, a belt extending from the receptacle and to and about the roller to convey a layer of paste from the receptacle and apply it to the grids moving through the passageway, and adjustable means for controlling the thickness of the paste layer.

46. In a grid pasting machine, a passageway for the movement of grids therethrough, a paste receptacle, a roller adjacent the passageway, a belt extending from the receptacle and to and about the roller to convey a layer of paste from the receptacle and apply it to the grids

moving through the passageway, power means for driving the belt, a device for limiting the thickness of the paste layer to be conveyed by the belt, and means operative by said device for rendering the power means inactive.

47. In a grid pasting machine, a passageway for the movement of grids therethrough, a paste receptacle, a roller adjacent the passageway, a belt extending from the receptacle and to and about the roller to convey a layer of paste from the receptacle and apply it to the grids moving through the passageway, power means for driving the belt, a device for limiting the thickness of the paste layer to be conveyed by the belt, and means operative by said device for rendering the power means inactive, said limiting device including a roller disposed in the receptacle and cooperating with the belt surface.

48. In a grid pasting machine, a passageway for the movement of grids therethrough, a paste receptacle, a roller adjacent the passageway, a belt extending from the receptacle and to and about the roller to convey a layer of paste from the receptacle and apply it to the grids moving through the passageway, power means for driving the belt, a device for limiting the thickness of the paste layer to be conveyed by the belt, and means operative by said device for rendering the power means inactive, said limiting device including a cross member disposed transversely of the belt but spaced therefrom.

49. In a grid pasting machine, a passageway for the movement of grids therethrough, a paste receptacle, a roller adjacent the passageway, a belt extending from the receptacle and to and about the roller to convey a layer of paste from the receptacle and apply it to the grids moving through the passageway, power means for driving the belt, a device for limiting the thickness of the paste layer to be conveyed by the belt, and means operative by said device for rendering the power means inactive, said limiting device including a cross member disposed transversely of the belt but spaced therefrom, and a power driven roller adjacent the cross member.

50. In a grid pasting machine, a paste receptacle, a belt for conveying a layer of paste from the receptacle to the point of paste application to the grids, a plate forming one wall of the receptacle and vertically adjustable with respect to the belt to control the thickness of the paste layer, means for driving the belt, and means operative by an upward movement of the plate to stop the belt.

51. In a grid pasting machine, a main frame supporting a paste receptacle and applying mechanism at one end, a carriage unit at the other end of the machine supporting a grid feeding mechanism, guides extending longitudinally of the machine for slidably and adjustably mounting the carriage on the frame, a passageway for directing grids from the feeding mechanism to the applying mechanism, said passageway being formed in part by a pair of rollers extending transversely thereof and with one roller of the pair carried by the main frame and the other roller of the pair mounted on the carriage, and means for adjusting the carriage on said longitudinally extending guides to thereby adjust the opening between said rollers.

52. In a grid pasting machine, a main frame supporting a paste receptacle and applying mechanism at one end, a carriage unit at the other

end of the machine supporting a grid feed mechanism, guides extending longitudinally of the machine for adjustably mounting the carriage on the frame, a passageway for directing grids from the feeding mechanism to the applying mechanism, said passageway including a pair of rollers extending transversely thereof and with

one roller of the pair carried by the main frame and the other roller of the pair mounted on the carriage, a lever for adjusting the carriage on said guides, and an adjustable stop for limiting the carriage movement to thereby control the size ⁵ of the passageway.

ARTHUR D. LUND.
